UNITED STATES PATENT OFFICE.

JAMES J. FETZER, OF COLUMBIANA, OHIO, ASSIGNOR TO THE HERBRAND COMPANY, OF FREMONT, OHIO.

BODY-HANGER FOR VEHICLES.

SPECIFICATION forming part of Letters Patent No. 683,741, dated October 1, 1901.

Application filed August 12, 1901. Serial No. 71,827. (No model.)

To all whom it may concern:

Be it known that I, JAMES J. FETZER, a citizen of the United States, residing at Columbiana, in the county of Columbiana and State 5 of Ohio, have invented certain new and useful Improvements in Body-Hangers for Vehicles; and I do hereby declare the following to be a full, clear, and exact description of the invention, such as will enable others skilled 10 in the art to which it appertains to make and use the same.

My invention relates to the art of carriage-making, and has particular reference to improvements in hangers for securing the body 15 of a vehicle to its supporting-springs. It has further reference to hangers of the double type, as exemplified by United States Letters Patent No. 595,133, issued December 7, 1897, to Samuel R. Bailey, having a laterally-projecting spring-plate as the means of attachment. Hangers of this class have heretofore 20 been secured in position by bolts passing through the projecting spring-plate and spring. They have also been secured by 25 clips for binding the spring-plate to its supporting-spring; but so far as I am aware there has never before been a hanger invented or produced capable of universal attachment either by through-bolts or clips 30 without the necessity of changing the length of the vehicle-reach and its attachments.

The main object and purpose of my present invention, therefore, is the production of an interchangeable hanger capable of meeting 35 all requirements of the trade whether for a through-bolt or a clip attachment without alteration in the length of the vehicle-reach and irons.

A further object is the production of a 40 hanger of most compact and economical proportions, the body or bar whereof occupies a plane parallel with and immediately adjoining that occupied by its supporting-spring, this fixed relation between said spring and bar being at all times maintained regardless 45 of the mode of connecting them.

The invention will be hereinafter described, and particularly pointed out in the claims following.

50 In the accompanying drawings, which form part of this application, and whereon corre-

sponding letters of reference indicate like parts in the several views, Figure 1 represents in side elevation the running-gear of a vehicle with my improved body-hangers secured to 55 the springs, the reach being broken away for economy of space. Fig. 2 is an enlarged perspective view of my invention applied to an elliptic end spring. Fig. 3 is a vertical section through spring and hanger, taken on the line 60 3 3 of Fig. 2. Figs. 4 and 5 are detached views of the invention, representing the same in plan and in front elevation, respectively. Fig. 6 is a modification of the invention corresponding with Fig. 3, but showing the 65 hanger secured to its supporting-spring by through-bolts.

Reference being had to the drawings and letters thereon, A represents a vehicle-body, B a vehicle-reach, and C D front and rear 70 end springs, respectively, all of ordinary construction. Surmounting each spring C D is an attaching-plate E, integral with and projecting laterally from the hanger-bar F proper, which terminates in downwardly and 75 inwardly extending brackets G G, upon which latter the vehicle-body A rests and is secured either by clips or bolts, as the case may be.

H H represent clip-holes formed partly in plate E and partly in the bar F, thus perforating said plate and bar at their line of intersection, as best shown by Figs. 4 and 5 of the drawings. Passing through these holes H H are clips I I, of any approved construction, which are partially embedded in the surface 85 of bar F and encircle its plate E, thus securely binding the structure to its supporting-spring.

This being a description of my invention in its preferred form of construction and means 90 of attachment, it will be particularly noted that plate E may also be secured by means of through-bolts, as indicated by Fig. 6, in which event the width of plate E and the position of bar F with relation to its supporting-spring remains unaltered, so that as a consequence standard reach and reach-irons are employed regardless of whether the hanger is clipped or bolted in position.

Heretofore it has been impossible to convert a bolted hanger into one of the clip type, owing to the reduced width of its attaching-

plate. By my invention, however, this is readily and effectively accomplished by punching the clip-holes, as hereinbefore described, partly in the hanger-bar and partly in its attaching-plate, thus affording space for passage of the clips at one side without changing the relative location of the hanger-bar and without the necessity of employing reaches of different lengths.

10 Having thus described my invention, what I claim, and desire to secure by Letters Patent, is—

1. As an article of manufacture a body-hanger provided with a lateral attaching-plate

perforated by clip-holes extending into the 15 hanger-bar, substantially as described.

2. As an article of manufacture a body-hanger provided with a lateral attaching-plate having clip-holes formed partly in the plate and partly in the hanger-bar, substantially 20 as described.

In testimony whereof I subscribe my signature in presence of two witnesses.

JAMES J. FETZER.
